US00D815641S

(12) **United States Design Patent** (10) **Patent No.:** **US D815,641 S**
(45) **Date of Patent:** **** Apr. 17, 2018**

(54) **REMOVABLE SSD DEVICE**

(71) Applicant: **Sunland International, LLC**,
Campbell, CA (US)

(72) Inventor: **Murray Ellis, II**, Cupertino, CA (US)

(73) Assignee: **SUNLAND INTERNATIONAL, LLC**,
Campbell, CA (US)

(**) Term: **15 Years**

(21) Appl. No.: **29/545,218**

(22) Filed: **Nov. 10, 2015**

(51) LOC (11) Cl. **14-02**

(52) U.S. Cl.

USPC **D14/436**; D14/435

(57) **CLAIM**

The ornamental design for a removable SSD device, as
shown and described.

DESCRIPTION

FIG. 1 is a front-right perspective view of the removable
SSD device;
FIG. 2 is a front view of the removable SSD device;
FIG. 3 is a back view of the removable SSD device;
FIG. 4 is a right view of the removable SSD device;
FIG. 5 is a left view of the removable SSD device;
FIG. 6 is a top view of the removable SSD device; and,
FIG. 7 is a bottom view of the removable SSD device.

(Continued)

The broken lines shown represent unclaimed features of the removable SSD device and form no part of the claimed design.
